UNITED STATES PATENT OFFICE

IVAN N. KINNEY, OF SAN DIEGO, CALIFORNIA

AIRSHIP LANDING AND MOORING MAST

Application filed October 7, 1929. Serial No. 397,890.

My invention relates to airship landing and mooring masts, and the objects of my invention are: First, to provide an apparatus of this class which eliminates the need of a ground crew for landing or mooring airships; second, to provide an apparatus of this class which enables an airship to discharge or take on freight or passengers without bringing the gondolas, doors or cabin close to the ground so they might be damaged by striking the ground if currents of air should cause the air ship to settle slightly; third, to provide an apparatus of this class which enables an airship to anchor at night as well as in the day; fourth, to provide an apparatus of this class which readily receives an anchor dropped from the airship and guides it into a proper catching means; fifth, to provide an apparatus of this class which may be rotated so as to face the wind; sixth, to provide an apparatus of this class which greatly reduces the space needed to land or moor an airship; seventh, to provide an apparatus of this class which might readily be mounted upon a building or other structure, thereby enabling the airship to anchor over the business section of a town; and eighth, to provide on a whole a novelly constructed apparatus of this class which is extremely simple of construction, proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a plan view of my airship landing and mooring mast; Fig. 2 is a side elevational view thereof; Fig. 3 is an enlarged fragmentary sectional view, showing the relationship of the turning table to the base; Fig. 4 is another enlarged fragmentary sectional view, showing the means for rotating

the turning table; Fig. 5 is a diagrammatical view, illustrating the manner in which a dirigible or other airship is landed and moored to my apparatus; Fig. 6 is an enlarged fragmentary sectional view through 6-6 of Fig. 1, showing the anchor catching portion of my apparatus; Fig. 7 is an enlarged fragmentary plan view of the anchor catching portion; Fig. 8 is a sectional view through 8-8 of Fig. 6; Fig. 9 is another sectional view through 9-9 of Fig. 6; Fig. 10 is a sectional view through 10-10 of Fig. 6; and Fig. 11 is a sectional view through 11-11 of Fig. 6.

Similar characters of reference refer to similar parts and portions throughout the several views of the drawings.

Base 1, track 2, turning table 3, rollers 4, ring gear 5, drive gear 6, gear and shaft mechanism 7, motor 8, tower 9, guide 10, anchor 11, anchor cable 12, shock absorber 13, anchor hoist 14, mooring mast 15, and elevator shaft 16, constitute the principal parts and portions of my airship landing and mooring mast.

My apparatus is supported on a base 1, which, in the structure shown, is formed of reinforced concrete and set flush with the ground of the landing field. The base 1 is provided with a circular depression 1^a. Supported in the side walls of the depression is an annular track 2. The track 2 is channel shaped in cross section with one leg thereof arranged above the other so as to form upper and lower rollways 2^a and 2^b.

The turning table 3 is mounted within the depression 1^a and is provided with a flat upper surface 3^a which is substantially flush with the upper surface 1^b of the base surrounding the depression 1^a. Supported at the lower side of the turning table in spaced apart relation are a plurality of rollers 4 which normally ride on the lower flange or rollway 2^a of the track member 2, but which, should the turning table tend to lift out of the base, will ride on the upper flange or rollway 2^b of the track. The turning table is also supported relative to the base member 1 by a centrally located hub 4^b.

Positioned at the bottom side of the de-

pression 1^a, near its outer margin, is a ring gear 5, upon which is adapted to travel one or more drive gears 6 which are operated through suitable gear and shaft mechanism 7 by one or more motors 8, as shown best in Fig. 4.

Supported upon the turning table 3 is a tower 9. Secured to the upper end of the tower and extending downwardly and outwardly therefrom until it joins the turning table 3 is a guide 10.

As shown in Fig. 11, the guide is channel shaped in cross section with a flat floor 10^a and upwardly extending side walls 10^b which terminate in thickened and rounded upper edges 10^c. The lower end 10^d forms the mouth or intake end of the guide. This end is tangential with the surface of the turning table. From this end it curves upwardly towards the top of the tower 9. As shown in Fig. 1, the guide is fan shaped in plan with the mouth portion forming the widest end.

Outwardly from the tower, as shown best in Figs. 6 and 7, the guide decreases its slope and the walls 10^b increase in height. At this portion the upper margins of the side walls 10^b curve inwardly so as to restrict the opening at the upper side of the guide, as shown in Fig. 10. The side walls, together with the floor 10^a, form a funnel shaped throat portion 10^e, as shown in Figs. 6 and 9. The rear end of the throat portion joins a tube 10^f of annular cross section which is just large enough to receive a spherical anchor, to be described hereinafter. The tube slopes upwardly and rearwardly toward the tower. Above the funnel portion 10^e and the tube 10^f, the side walls 10^b, as shown in Figs. 6, 8, and 9, form a slit 10^g which intersects said funnel portion and tube. The slit is just wide enough to accommodate a cable connected to the anchor. The walls of the slit 10^g increase in height until their upper margins, which form a continuation of the rounded edges 10^c are above the tower 9. Short of the end of the tube, the slit 10^g terminates and is provided with a rounded rear upper marginal portion 10^h over which the anchor cable can travel.

The anchor 11, which is adapted to be lowered from an airship A by means of a cable 12, is spherical. The anchor is dragged along the ground and into the mouth of the guide by the cable 12 whereupon the side walls 10^b guide the ball into the throat 10^e. From here the anchor enters the tube 10^f while the cable extends out the slit 10^g.

Just forward of the throat portion 10^e before the walls 10^b of the guide have come together closer than the diameter of the anchor, the floor 10^a is provided with a sump or depression 10ⁱ, the forward wall of which is substantially vertical, while the rear wall

slopes upwardly and forms the lower side of the funnel portion 10^e, as shown best in Figs. 6, 9 and 10. The purpose of the sump is to prevent the anchor from rolling out of the tube 10^f and on down to the guide member 10.

Mounted within the tube 10^f is a shock absorber 13, which comprises a cylindrical end member 13^a adapted to reciprocate within the tube 10^f, the forward face 13^b of which is dished or concave slightly so as to fit the one side of the anchor ball 11. The cylindrical member 13^a may be made hollow and receive a spring 13^c which extends rearwardly therefrom to the rear end of the tube portion 10^f.

The tower 9 surrounding the anchor catching portion of the guide is provided with a loading and unloading platform 9^a. Extending from the forward side of the platform 9^a adjacent to the side of the catch portion 10^e of the guide 10 is a balcony 9^b. Supported at the extended end of the balcony 9^b is an anchor hoisting means 14 which may be raised and lowered by hydraulic pressure if desired. This means 14 is adapted to be swung over the sump 10ⁱ so as to hoist out the anchor 11.

Rearwardly of the catch portion 10^e and supported by the tower 9 is a mooring mast 15 which can be arranged to be raised or lowered, so that when it is lowered it does not interfere with the anchor cable 12 when said anchor cable extends out the slit 10^g. The mooring mast 15 may be readily raised and lowered by means of the hydraulic pressure means which also operates the davit.

Below the platform 9^a is another platform 9^c which is connected with the platform 9^a by steps 9^d. An elevator shaft 16 is provided which extends between the turning table 3 and the lower platform 9^c.

The operation of my apparatus is as follows: When it is desired to land an airship, the turning table 3 is rotated until the guide faces and is centered relative to the prevailing wind. The dirigible or airship landing maneuvers so as to pass over the apparatus in substantially centered relation to the guide 10. Before reaching the apparatus, the anchor 11 by means of the cable 12 is lowered to the ground and is pulled along by the airship as it moves over the apparatus. By reason of the wide lower end of the guide 10, it is quite easy to drop the anchor in such a manner that it is brought between the side walls 10^b of the guide. Continued movement of the dirigible, which is as slow as possible, causes the anchor to drag up the guide into the funnel shaped throat portion 10^e and into the tube 10^f. As soon as the anchor has passed into the throat portion 10^e of the guide, it cannot escape therefrom as the cable extends upwardly and rearwardly in the slit 10^g which is not wide enough to pass

the anchor. Continued movement of the dirigible causes the anchor to compress the spring 13° bringing the airship to a stop. If desired, a suitable winch may be mounted in the airship so that the cable or line may be let out should the airship be moving a little too fast to be brought to a stop within the movement allowed by the spring 13°. When the airship has been brought to a stop, it is substantially in the position indicated by the dotted lines B, though usually considerably higher relative to the apparatus. The cable is then reeled in causing the airship to move in reverse direction which brings the nose of the airship down to the position indicated by dotted lines C in Fig. 5, whereupon the mooring mast 15 is raised and secured in the usual manner to the nose of the dirigible. After the airship is once secured to the mooring mast, all strain on the cable 12 is released allowing the anchor to roll back to the sump 10 so it can be removed by use of the davit 14. The mooring mast may be arranged so as to rotate independently of the turning table, thereby enabling the dirigible to swing with the wind.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an apparatus of the class described, a tower, an anchor means releasable from an airship, an anchor catching mechanism mounted on said tower arranged to receive said anchor means, and guide means for directing said anchor means into said catch mechanism.

2. In an apparatus of the class described, a tower, an anchor means releasable from an airship, an anchor catching mechanism mounted on said tower arranged to receive said anchor means, guide means for directing said anchor means into said catch mechanism, and shock absorber means cooperating with said catch mechanism for de-accelerating said anchor means.

3. In an apparatus of the class described, an inclined guide means, comprising a flared lower portion and a constricted upper portion, and an anchor catching mechanism joining said constricted upper portion, said guide means adapted to receive an anchor from a moving airship and guide said anchor into said catch mechanism.

4. In an apparatus of the class described, an inclined guide means, comprising a flared lower portion and a constricted upper por-

tion, an anchor catching mechanism joining said constricted upper portion, said guide means adapted to receive an anchor from a moving airship and guide said anchor into said catch mechanism, and shock absorbing means cooperating with said catch mechanism for de-accelerating said anchor. 70

5. In an apparatus of the class described, a tower, an anchor means releasable from an airship, an anchor catching mechanism mounted on said tower arranged to receive said anchor means, guide means for directing said anchor means into said catch mechanism, and a rotatable table supporting said tower and guide means. 75

6. In an apparatus of the class described, a tower, an anchor means releasable from an airship, an anchor catching mechanism mounted on said tower arranged to receive said anchor means, guide means for directing said anchor means into said catch mechanism, shock absorber means cooperating with said catch mechanism for de-accelerating said anchor means, and a rotatable table supporting said tower and guide means. 80

7. In an apparatus of the class described, an inclined guide means, comprising a flared lower portion and a constricted upper portion, an anchor catching mechanism joining said constricted upper portion, said guide means adapted to receive an anchor from a moving airship and guide said anchor into said catch mechanism, and means for rotating said guide means so that said guide means faces into the wind. 85

8. In an apparatus of the class described, an inclined guide means, comprising a flared lower portion and a constricted upper portion, an anchor catching mechanism joining said constricted upper portion, said guide means adapted to receive an anchor from a moving airship and guide said anchor into said catch mechanism, shock absorbing means cooperating with said catch mechanism for de-accelerating said anchor, and means for rotating said guide means so that said guide means faces the wind. 90

In testimony whereof, I have hereunto set my hand at San Diego, California, this 24th day of September, 1929. 105
